UNITED STATES PATENT OFFICE.

HERBERT M. HAINLINE, OF SCIOTA, ILLINOIS.

COMBINATION LOCK.

Application filed July 9, 1923. Serial No. 650,438.

To all whom it may concern:

Be it known that I, HERBERT M. HAINLINE, a citizen of the United States, residing at Sciota, in the county of McDonough and

5 State of Illinois, have invented a new and useful Combination Lock, of which the following is a specification.

This invention relates to permutation locks, and more particularly permutation 10 padlocks.

The primary object of the invention is to provide a padlock of this character which may be readily and easily operated by persons familiar with the combination, but one 15 which will not yield under ordinary conditions when operated by unauthorized persons.

Another object of the invention is to provide a permutation lock wherein it will be 20 impossible to remove the same by disassembling the elements thereof.

A still further object of the invention is the provision of a novel form of shackle wherein the shackle together with its sup- 25 port may be moved longitudinally of the body of the lock in order to release the same.

With the foregoing and other objects in view which will appear as the description proceeds, the invention resides in the combination and arrangement of parts and in the details of construction hereinafter described and claimed, it being understood that changes in the precise embodiment of the invention herein disclosed, may be 30 made within the scope of what is claimed, without departing from the spirit of the invention.

Referring to the drawings:—

Figure 1 is a longitudinal sectional view 40 through a padlock constructed in accordance with the invention.

Figure 2 is a longitudinal sectional view through the padlock taken at right angles to Figure 1.

45 Figure 3 is a sectional view taken on line 3—3 of Figure 2.

Figure 4 is a side elevational view of a padlock.

50 Figure 5 is an elevational view of the elements constituting the lock showing the same in disassembled positions.

Figure 6 is an elevational view of one of the locking disks.

55 Figure 7 is an elevational view of one of the tumblers.

Figure 8 is a side elevational view of one of the stationary spacing disks.

Figure 9 is a sectional view taken on line 9—9 of Figure 2.

Referring to the drawing in detail, the 60 body portion of the lock includes members 5 and 6 respectively, the members 5 and 6 being preferably circular in formation. Member 5 is provided with an extension 7 formed with external threads 8 disposed adjacent to one end thereof, which threads accommodate the internal threads of the member 6, to secure the members 5 and 6 together.

Formed in the member 5 is an opening ex- 70 tends throughout the length thereof, which opening accommodates the plug or shackle support 9 formed with a cut out portion 10 adjacent to one end thereof, to receive the movable locking dog 11. This lock-

75 ing dog 11 is formed with a plurality of teeth 12, each of which having an inclined edge and a relatively straight edge, the relatively straight edges being indicated at 13. The straight edges present shoulders to contact with the tumblers and prevent movement of the plug or shackle support 9, when the shackle is in its locked position.

80 It will also be noted that due to this construction the shackle support may be inserted in the body 5, the locking dog 11 moving into the cut out portion 10 as the teeth move past the tumblers. As shown, the locking dog 11 is of a width less than the depth of the cut out portion 10 to permit the locking dog to 85 move to a position where the ends of the teeth 12 will lie below the upper edge of the shackle support 9 when the plug or shackle support 9 is to be removed.

85 The construction of the members 5 and 95 6 is such as to provide a space between the adjacent edges thereof, which space accommodates the tumblers 14, and while only two tumblers and locking disks have been illustrated and described in this specification, it is to be understood that the number 100 of tumblers and locking disks may be varied according to the size of the lock.

105 The tumblers 14 are of the rotatable type and provided with graduations on their peripheries the inner edges of the tumblers being cut away to provide notches 15 that receive the tongues 16 of the locking disks 17, thereby presenting a structure wherein the locking disks will fit within the tum- 110

blers to change the combination by moving the locking disks with respect to their tumblers, thereby moving the notches 18 of the locking disks with respect to the tumblers and graduations on the peripheries thereof.

Associated with each tumbler is a stationary spacing disk indicated at 19, which disks have inwardly extending tongues 20 adapted to move in the grooves 21 of the 10 shackle supporting member 9 to hold the spacing disks against rotary movement. A notch portion 22 is formed in each spacing disk 19, which notches are adapted to aline with the notches 18 of the locking disk to 15 allow the locking dog and the shackle supporting member 9 to move longitudinally through the body portion of the lock.

Relatively thin spacing disks 23 hold the tumblers in spaced relation with each other, 20 the spacing disks 23 being provided with notches to permit the dog 11 to pass therethrough. Tongues 24 are provided on the spacing disks 23 and extend laterally to contact with the lugs 25 of the tumblers so 25 that the tumblers may be operated in an anti-clockwise direction to indicate the starting point when operating the lock in the dark. In order that the locking dog 11 will be normally urged to the limit of its 30 outward movement, a spring member 26 is disposed between one wall of the cut out portion 10 and lower edge of the dog 11.

Formed in the member 6 is a groove 27 that accommodates the locking dog 11, and 35 since the member 6 is threaded on the member 5, it is obvious that the locking dog contacting with one of the side walls of the groove 27 will prevent disconnecting the members 5 and 6 unless the locking dog 11 40 has been moved within the confines of the cut out portion 10. Screws 28 pass through threaded openings in the member 6 and have their inner ends positioned in the openings 29 of the member 5 thereby 45 insuring the aligning of the notches and grooves of the member 6 and tumblers, when the elements of the lock are assembled.

The pivoted shackle is indicated at 30 and 50 has one end thereof connected to the shackle support 9 at 31, the opposite end of the shackle being relatively straight at 32 to move within the cut out portion 33 of the shackle support 9 to lock the shackle against 55 movement. To facilitate the operation of the lock in the dark, each spacing disk 19 is supplied with a spring arm 34 that carries a pin 35 extending through a suitable opening therein, the pins having their outer ends 60 curved and extended beyond the periphery of the locking disk associated therewith, so that as the tumblers operating thereover, are moved, the fingers 36 formed between

the notches 15 will engage the pin 35 and restrict movement of the tumblers to a degree, 65 whereby the operator may be notified at each movement of the tumbler.

A handle 37 is formed integral with the member 6 and affords means for the operator to grip and hold the box stationary 70 while the tumblers are being operated. From the foregoing it will be obvious that when it is desired to operate the lock, the tumblers are moved to their proper positions to cause the notches of the locking disks connected thereto, to move into alignment providing a path for the locking dog 11 and permitting the shackle supporting member 9 to move to a position as indicated in dotted lines in Figure 3 of the drawings, 80 whereupon the shackle may be moved to its unlocked position.

What is claimed as new is:—

1. A permutation lock including a sectional body portion, one of said sections having a threaded extension, the opposite extension having threads to receive the threaded extension to connect the sections, tumblers and locking disks supported on the threaded extension, a shackle supporting member movable through the body portion, locking dogs on the shackle supporting member and adapted to cooperate with the locking disks to restrict movement of the shackle supporting member, said locking disks having notches adapted to register to allow the locking dogs to move therethrough, and a pivoted shackle on the shackle supporting member.

2. A permutation lock including a sectional body portion, one of said sections having an extension formed with threads, the opposite section having a threaded opening to receive the threads of the extension, the section having the threaded opening having a groove formed in the wall thereof, a shackle supporting member adapted to move longitudinally of the body portion, a locking dog carried by the shackle supporting member and adapted to move in the groove of the section of the body having the threaded opening to restrict rotary movement of the sections with respect to each other, tumblers mounted between the sections, locking disks controlled by the tumblers, said locking disks adapted to cooperate with the locking dog to restrict movement of the shackle supporting member with respect to the body portion.

In testimony that I claim the foregoing 120 as my own, I have hereto affixed my signature in the presence of two witnesses.

HERBERT M. HAINLINE.
